Application November 23, 1929, Serial No. 409,298

27 Claims. (Cl. 175—363)

My invention relates to mercury arc rectifier systems and particularly to D.-C. voltage regulation in such systems.

The control of D.-C. voltage in the mercury arc rectifier has commonly been accomplished heretofore by regulation of the rectifier A.-C. supply, either by step-by-step regulation of the A.-C. voltage applied to the rectifier transformer or by phase regulation. These methods are open to the objection that the resulting control of the D.-C. voltage is not of sufficiently fine degree or that the regulating means do not follow with sufficient closeness the changes in the D.-C. load current. Other methods, also operating by regulation of the A.-C. voltage and having for their object a finer degree of D.-C. voltage control, are open to the objection that they involve the use of expensive and complicated control devices.

It is the object of my invention, therefore, to provide improved means for regulating the voltage of the mercury arc rectifier. A particular object of the invention is to provide means for regulation of the rectifier D.-C. voltage by control of the electric field between the cathode and anodes.

In carrying my invention into effect, regulation of the D.-C. rectifier voltage is accomplished by impressing potentials upon control grids placed between the rectifier cathode and anodes.

Further objects and advantages of the invention will be apparent and a clearer understanding thereof will be obtained from the following description taken with the accompanying drawings in which

Figure 1 is a diagrammatic view of rectifier apparatus including a D.-C. voltage control circuit and illustrating an embodiment of the invention;

Figs. 2 and 3 are detail views of grid connections in the rectifier apparatus shown in Fig. 1;

Figs. 4 and 5 are voltage diagrams illustrating the operation of the system shown in Fig. 1;

Figs. 6 and 7 illustrate modifications of the D.-C. voltage control circuit shown in Fig. 1;

Figs. 8, 9 and 10 are diagrammatic views of automatic D.-C. voltage regulation means for the system shown in Fig. 1;

Figs. 11 and 13 are voltage diagrams illustrating the effect on D.-C. regulation of a grid voltage wave having a steep wave front, and Fig. 12 is a diagrammatic view of a rectifier apparatus operating in accordance with diagrams 11 and 13;

Fig. 15 is a voltage diagram illustrating the effect on D.-C. regulation of harmonic grid voltages, and Fig. 14 is a diagrammatic view of rec-

tifier apparatus operating in accordance with diagram 15;

Fig. 17 is a voltage diagram illustrating D.-C. regulation by variation of the A.-C. grid potential, and Figs. 16 and 18 are diagrammatic views of rectifier apparatus operating in accordance with diagram 17;

Fig. 20 is a voltage diagram illustrating D.-C. voltage regulation by phase shifting of A.-C. grid voltages and Fig. 19 illustrates rectifier apparatus operating in accordance with Fig. 20;

Fig. 21 is a diagrammatic view illustrating a modification of the invention in which the D.-C. voltage control circuit is connected to the rectifier transformer neutral, and Fig. 22 is a voltage diagram illustrating the operation of the system shown in Fig. 21;

Figs. 23 and 24 are diagrammatic views illustrating respectively D.-C. voltage control circuits for maintaining a constant current in the load circuit of a rectifier and for limiting the load current.

Fig. 25 is a voltage diagram illustrating a modification of the systems shown in Figs. 4 and 5.

Figure 1 shows a rectifier 1 comprising anodes 2 to 7, control electrodes, as grids 8 to 13, associated with anodes 2 to 7 respectively, and cathode 14. The anodes are supplied with current from transformer 15 having a primary 16 and secondary 17 with neutral point 18. The control electrodes 8 to 13 are connected to a polyphase A.-C. supply. In the present embodiment of the invention, the supply for the control electrodes comprises auxiliary windings 19 of rectifier transformer 15, but the said supply may also be obtained from a separate transformer. Current limiting means, as resistances 20, may be inserted in the control electrode leads. The neutral point 21 of the auxiliary windings is connected to the negative pole of battery 22, the positive pole of which is connected to the cathode 14. The potential of the battery may be varied as by changing the position of connection 23.

Fig. 2 shows in detail one of the anodes, as 2, connected to anode plate 24. A sleeve 25 surrounds anode 2 and its corresponding control electrode, as grid 8, the latter being supported on the sleeve by insulators 26. A grid terminal 27 is connected to grid 8 through conductor 28 and conductor 29. Terminal 27 is fastened to the conductor as by screw 30. Conductor 28 passes through bushing 31 located in the anode plate and is prevented from turning in the bushing by locking plate 32, which is in fixed relation with the conductor and is held in a slot 33 formed in the

bushing. The washer 34 is placed between plate 32 and the lower end of the bushing. Conductor 28 is locked to the bushing by nut 35 which projects downwardly within a recess 36 of the bushing and bears against washer 37. The joint between conductor 28 and bushing 31 is sealed by mercury placed between nut 35 and the walls of the recess 36. The portion of conductor 28 which projects below the bushing is surrounded by a sleeve 33 supported on insulating bushing 31. The conductor 28 joining grid 8 and conductor 28 is enclosed in a sleeve 39, of glass or other suitable insulating and heat-resisting material, which is located at its ends in sleeves 25 and 38. Figure 3 shows a control electrode terminal structure similar in all respects to that shown in Fig. 2 except that two sets of terminals 27, conductors 28, conductors 29 and insulating sleeves 39 are located in a single insulating bushing 40 surrounded by a single sleeve 41.

In operation of the system shown in Fig. 1, the anodes 2 to 7 are supplied from the secondary windings 17 of transformer 15. The anodes will successively assume a maximum positive potential and will, therefore, carry current in sequence. As indicated in Fig. 4, in which E_2 , E_3 , E_4 . . . represent the voltage waves of anodes 2, 3, 4 . . . with respect to the rectifier transformer neutral 18, the arc is transferred from anode to anode at the points of intersection X. The D.-C. voltage is equal at any instant to the voltage of the anode carrying current (minus the voltage drop in the arc) and has the value represented by the succession of waves E_2 , E_3 , E_4 . . . intersecting at points X and the resultant average D.-C. voltage is as shown by the dotted line V.

If, however, the electric field between cathode 14 and a given anode is modified by maintaining the potential between the cathode and said anode, for example, anode 4, lower than the potential between the cathode and the preceding anode, until some point, as b, beyond the intersection X of the waves E_3 , E_4 is reached, the current flow will be transferred from anode 3 to anode 4 only after said intersection point is reached. As a result, the shape of the D.-C. voltage wave will be altered, thereby altering the magnitude of the average D.-C. voltage.

Assuming that anode 3, corresponding to wave E_3 of Fig. 4 is carrying current: if a potential is applied to grid 10 of the succeeding anode 4, of such value as to reverse or neutralize the electric field between the cathode and said anode 4, until any desired point on the wave E_4 , for example, point b, is reached, the arc will not be transferred from anode 3 to anode 4 until said point b on wave E_4 is reached. The shape of the succession of voltage waves will, therefore, be altered, as shown by the heavy line in Fig. 4, and the average D.-C. voltage will have a value as shown by line B. If the potential on grid 10 of anode 4 is maintained until other points on wave E_4 , as a or c, are reached, the shape of the voltage wave is altered accordingly and the average D.-C. voltage assumes the values shown by A and C, respectively. The potential of a given grid, as grid 10 of anode 4, with respect to cathode 14, at any instant, is equal to the potential at that instant of that phase of the auxiliary A.-C. supply 16 to which said grid is connected, minus the potential of battery 22. At the instant when the grid has a positive A.-C. potential equal to the battery potential, the grid's potential to the cathode is zero. In Fig. 5 the sine waves

E_3 , E_4 . . . represent the potential of the corresponding anodes 3, 4 . . . to the neutral 18 of the rectifier supply transformer 15. The sine wave G_4 represents the A.-C. potential of a grid, as grid 10, to the neutral 21 of the auxiliary windings 19. If the potential of battery 22 has the value E_2 , the potential of grid 10 with respect to the cathode 14 is equal to zero at point b_2 corresponding to point b_1 of anode voltage wave E_4 . Before the point b_2 is reached, grid 10 has a negative potential with respect to the cathode, and the transfer of the arc from anode 3 to anode 4 is, therefore, prevented. When point b_2 is passed, the potential of grid 10 to the cathode is positive and the arc is, therefore, transferred from anode 3 to anode 4. When the battery potential has the value E_1 , the grid potential to the cathode is equal to zero at the point a_2 , and the arc will be transferred to anode 4 at a_1 of wave E_4 . When the battery potential has the value E_3 , the grid potential to the cathode is zero at point c_2 , and the arc is transferred to anode 4 at c_1 of wave E_4 .

It is evident, therefore, that the transfer of the arc from anode to anode may be controlled by varying a D.-C. voltage, as that of battery 22, which is in series with the A.-C. voltage impressed on the grids and that the rectifier D.-C. voltage may thereby be controlled.

Instead of varying the D.-C. voltage in series with the grids by taps on the battery 22, as shown in Fig. 1, a potentiometer 42 connected across the battery may be employed, as shown in Fig. 6. Further, instead of employing a separate source of D.-C. potential, as a battery 22, for the purpose set forth in connection with Fig. 1, the D.-C. output voltage of the rectifier may be utilized by employing a potentiometer 43 connected across the rectifier D.-C. conductors, as shown in Fig. 7. The neutral point 21 of the auxiliary windings 19 is, in this latter embodiment, connected to the potentiometer and the rectifier D.-C. voltage thereby controlled by varying the position of connection 23. A reactor 44 may be connected in series with the potentiometer to smooth out the current flow therein and thus prevent the ripple of the rectifier output D.-C. voltage from being impressed on the control grids.

It is frequently desirable that the regulation of the rectifier output D.-C. voltage be accomplished automatically. To this end, Fig. 8 illustrates a portion of the system of Fig. 1 incorporating the potentiometer of Fig. 7 and with the addition of automatic control means comprising a voltage regulator 45. The regulator acts to short-circuit more or less of the resistance 43 connected across the rectifier D.-C. output conductors, thus varying the D.-C. potential on the grids. A current transformer 46, associated with the rectifier transformer, as with one phase of the primary, actuates the regulator. The rectifier D.-C. output voltage is thereby automatically controlled in function of the load.

Figure 9 shows another embodiment of the invention for automatically controlling the rectifier D.-C. output voltage, which is similar to that shown in Fig. 8, but differs therefrom in that a voltage coil 47, connected across the rectifier D.-C. output voltage conductors, actuates the regulator 45 to maintain automatically constant the rectifier D.-C. output voltage under all load conditions.

Figure 10 shows another embodiment of the invention for automatically controlling the recti-

ifier D.-C. output voltage. In this embodiment, the regulator 45 is provided with two coils, one of which, 47, is actuated as in Fig. 9, in accordance with the rectifier D.-C. output voltage. The other, 48, is connected in one of the rectifier D.-C. output line conductors in parallel with a shunt 49 and actuated in accordance with the rectifier output load current.

In order to obtain a closer and more stable regulation of the rectifier D.-C. output voltage, I have found it to be desirable that the A.-C. potential impressed on the grids have a steep wave front within the regulating range. By regulating range is meant the range through which the A.-C. potential impressed on a grid intersects the D.-C. potential impressed thereon, as shown, for example, by points a_2 b_2 c_2 on the grid potential wave G_4 of Fig. 5. Undesirable variations in the D.-C. potential impressed on the grids, which tend to produce instability in the rectifier D.-C. output voltage control, may be produced either by variation in the voltage of the D.-C. source employed for impressing potentials on the grids, or by inaccuracies of the regulator employed for controlling said D.-C. voltage. Instability may also result from variations in the electric fields in the rectifier or from changing pressure and temperature conditions in the rectifier. The effect of the grid A.-C. potential wave shape on the stability of the rectifier D.-C. output voltage regulation is shown in Fig. 11. In this figure E_4 represents the voltage wave of an anode, as anode 4, and G_5 G_6 represent differently shaped grid voltage waves of the corresponding grid 10. The wave fronts of waves G_5 and G_6 are, respectively, relatively flat and relatively steep. If the grid operates with the wave G_5 having a flat wave front, any accidental variation of the normal D.-C. grid potential d , as between the values d_1 d_2 , will cause a comparatively large variation v_1 of the time of transfer of the arc from anode to anode. If, however, the grid operates with the wave G_6 having the steeper wave front, the varying of the grid potential between the limits d_1 d_2 will cause only a small variation v_2 in the time of transfer of the arc from anode to anode. Therefore, by using a steep A.-C. voltage wave on the grid, undesirable variations of the grid D.-C. voltage will have a negligible effect on the value of the rectifier D.-C. output voltage.

An A.-C. potential having a steep wave shape over the regulating range may be obtained by supplying to the grid an A.-C. voltage lagging in phase behind the voltage impressed on the anode with which it is associated. One means of obtaining the desired A.-C. grid potential is shown in Fig. 12 in which the connections from the auxiliary winding 19 to grids 8, 9, 10 . . . are displaced relatively to said connections shown in Fig. 1 and as indicated by the heavy line connection between grid 8 and neutral point 21 in Figs. 1 and 12. The connections are so arranged that the A.-C. voltage applied to a given grid, as grid 10, corresponding to anode 4, lags 60 degrees in phase behind the voltage of said anode.

The effect of the change in connections, as shown in Fig. 12, is made clear in Fig. 13 in which E_4 represents the voltage wave of anode 4, and G_7 that of the corresponding grid 10. Since grid voltage wave G_7 lags behind anode voltage wave E_4 , the zero grid voltage points a_4 b_4 c_4 corresponding to the varying D.-C. potentials B_4 B_5 B_6 impressed on the grid, will occur on the steep

portion of the grid voltage wave. The effect, therefore, on the stability of the rectifier D.-C. output voltage regulation will be as hereinbefore explained in connection with Fig. 11.

The phase position of the grid voltages with respect to the anode voltages should be selected to suit the regulating range required, and will depend on the number of phases used, the type of transformer connections and other factors. The invention is, therefore, not to be limited to the particular structure described in Fig. 12 but includes all other equivalent arrangements.

An A.-C. grid potential having a steep wave front over the regulating range may further be obtained by impressing on the grids a voltage corresponding in frequency to a harmonic of the A.-C. voltage impressed on the anodes, for example, a third harmonic. A grid voltage comprising the harmonic together with the fundamental may be produced by oversaturating the grid auxiliary transformer such as shown in Fig. 12. A harmonic grid voltage without the fundamental may be produced as shown in Fig. 14. In the latter figure the auxiliary transformer is oversaturated and the primary 51 is connected in Δ with insulated neutral and the secondaries 52 in open delta. The voltages of the fundamental frequency are, therefore, canceled out, leaving only the harmonic voltages.

The operation of the system shown in Fig. 14 may be better understood by reference to Fig. 15. By employing a third harmonic A.-C. voltage on the grids in Fig. 14, the voltages of grids 8, 10 and 12, corresponding to the anodes 2, 4 and 6 will be of one phase, while the voltages of grids 9, 11 and 13, corresponding to anodes 3, 5 and 7, will be of another phase displaced 180 degrees from the phase of grids 8, 10 and 12. The grid voltage waves are of steep wave front, for example, G_8 , corresponding to anode voltage wave E_4 . The zero points a_8 b_8 and c_8 are located on the steep front of wave G_8 , said points corresponding to the varying D.-C. potentials B_7 B_8 B_9 impressed on the grids. The resulting effect on the stability of the rectifier D.-C. output voltage regulation is as hereinbefore explained in connection with Figs. 11 and 13.

In the systems shown in Figs. 12 and 14, the potentiometer connection across battery 22 may be used, as shown in Fig. 6, or the battery may be dispensed with by employing the potentiometer connection across the rectifier D.-C. line, as shown in Fig. 7. Further, in the regulating means shown in Figs. 12 and 14, the rectifier D.-C. output voltage may be automatically controlled, for example, by the regulating means shown in Figs. 8, 9 and 10.

In the foregoing, the regulating of the rectifier D.-C. output voltage is accomplished by impressing on the grids D.-C. potentials in series with A.-C. potentials and varying the magnitude of the D.-C. potential. Instead of varying the D.-C. potential impressed on the grids, the same result may be obtained by varying the magnitude of the A.-C. potential impressed thereon, either of fundamental or harmonic frequency, while maintaining the D.-C. potential constant. Fig. 16 shows means for regulating the rectifier D.-C. output voltage in this latter manner, including an auxiliary transformer 53 for impressing A.-C. potentials on the grids comprising primary 51 and secondary 54. This auxiliary transformer is provided with an exciting winding 55 in the rectifier D.-C. output load circuit. The load current passing through the exciting winding 55

saturates the core of the auxiliary transformer which introduces a harmonic component, for example, the third harmonic in the voltage wave of secondary 54. The magnitude of the harmonic voltage is a function of the load current. At small loads the harmonic voltage is small, and at greater loads it is increased in magnitude.

Fig. 18 shows a regulating means similar to that of Fig. 16, the D.-C. voltage impressed on the grids again being constant while the A.-C. potential impressed thereon is varied by means of the exciting winding 55 which saturates the core of the auxiliary transformer 50 and produces thereby a harmonic voltage in the secondary winding of the auxiliary transformer 50. In the regulating means of Fig. 18, however, the transformer is of the form shown in Fig. 14. The voltages of the fundamental frequency are, therefore, canceled out in the system of Fig. 18, leaving only the harmonic voltages to be impressed on the grids.

Referring to Fig. 17 in connection with Fig. 18, the waves G_9 represent different values of a harmonic grid voltage wave in the system of Fig. 18, and E_4 the corresponding anode voltage wave. With a constant D.-C. voltage B_{10} impressed on the grid, then for varying values of A.-C. grid voltage, the corresponding zero grid voltage points are a_7 b_7 c_7 and the corresponding arc transfer points are a_8 b_8 c_8 . Since, therefore, the position of the arc transfer point varies with the load current, the rectifier D.-C. output voltage is varied therewith, as explained in connection with Fig. 4. As a further refinement, non-inductive resistances or reactance coils, as 56, may be inserted in series with the primary windings to reduce the exciting voltages of transformer 53.

It will be noted that in the rectifier D.-C. output voltage regulating means, shown in Figs. 16 and 18, it is possible to compensate for the drop in the D.-C. output voltage of the rectifier, and thereby to secure either a relatively constant voltage characteristic over the working range or a voltage characteristic rising at increasing loads, that is, an "over-compounded" characteristic.

In the regulating means shown in Figs. 16 and 18, the regulation of the rectifier D.-C. voltage output is secured automatically. The regulation may be accomplished by other means, operated manually if preferred, to vary the A.-C. potential impressed on the grids, while maintaining constant the D.-C. potentials impressed thereon. For example, the A.-C. potential impressed on the grids may be varied by taps 57 on the primary 51 of transformer 50, as shown in Fig. 18. Further, instead of using a separate source of D.-C. grid voltage, as battery 22, either as shown in Figs. 16 and 18 or with the potentiometer across the battery, as shown in Fig. 6, the battery or other separate D.-C. voltage source may be dispensed with, and the D.-C. output voltage of the rectifier utilized by means of the potentiometer across the rectifier line, as shown in Fig. 7.

In the rectifier D.-C. output voltage regulating means hereinbefore described, the regulation is accomplished by varying the magnitudes of either the D.-C. or the A.-C. potentials impressed on the grids. The rectifier D.-C. output voltage may, however, be controlled without change in the magnitude of either the D.-C. or the A.-C. grid voltages by shifting the phase position of the A.-C. voltage impressed on the grids. Fig. 19 shows regulating means in which the poten-

tials impressed on the grids, both the D.-C., as battery 22 or other source of D.-C. potentials, and the A.-C. potentials, as from windings 19, are constant, and the rectifier D.-C. output voltage control obtained by means of a phase shifter 58 which may be interposed between primary 16 of the auxiliary transformer and secondary windings 19.

The operation of the rectifier D.-C. output voltage regulating means shown in Fig. 19 will be clear by reference to Fig. 20 in which E_4 represents the voltage wave of a given anode and in which G_{10} G_{11} G_{12} represent the different phase positions of the corresponding constant grid voltage wave. With a constant D.-C. grid potential B_{11} , and a constant A.-C. grid potential, the zero point of grid potential is shifted with the phase shift of the A.-C. grid potential wave. For A.-C. voltage wave positions G_{10} G_{11} G_{12} , the zero points are a_{10} b_{10} c_{10} , respectively, corresponding to the 20 arc transfer points a_9 b_9 c_9 of anode voltage wave E_4 . Since, therefore, the position of the arc transfer point varies with the phase position of the A.-C. grid potential wave, the rectifier D.-C. voltage is regulated accordingly.

In the structures hereinbefore described, embodying means for rectifier D.-C. output voltage regulation, the control circuit containing the sources of A.-C. and D.-C. potentials impressed on the grids is shown connected to the cathode. 30 Regulation of the rectifier D.-C. output voltage may also be effected by connecting the grid potential control circuit, not to the cathode, but to the rectifier transformer neutral point. Fig. 21 shows means for the regulation of the rectifier 35 D.-C. output voltage in which the grid potential control circuit, comprising a D.-C. voltage source, as battery 22, and an A.-C. voltage source, as auxiliary windings 21 of rectifier transformer 15, is connected to the neutral point 18 of the rectifier 40 transformer secondary 17.

The operation of the system shown in Fig. 21 will be understood by reference to Fig. 22. In the latter figure, voltage waves E_3 and E_4 represent the potential of anodes 3 and 4 with respect to the neutral. Assuming that the D.-C. potential impressed on the grids has a value B_{12} with respect to the neutral, the voltage wave of grid 10, corresponding to anode 4, will then be G_{13} . When anode 3, the anode next preceding anode 4, is operating, the cathode potential is substantially equal to the potential of said anode 3, minus the voltage drop in the arc. The cathode potential is indicated in Fig. 22 by the curve M lying below anode voltage wave E_3 . It will be seen that the voltage curve G_{13} of grid 10 intersects the cathode potential curve M at point m_1 . This is equivalent to saying that at point m_1 , the potential of grid 10 is equal to the cathode potential. Before point m_1 is reached, 60 the potential of grid 10 is less than that of the cathode, that is, the grid potential up to the point m_1 , is negative with respect to the cathode and does not become zero with respect thereto until point m_1 is reached. Since the arc cannot 65 be transferred to anode 4, the next anode following anode 3, as long as its grid 10 is negative with respect to the cathode, the arc is transferred to said anode 4 only when zero point m_1 is reached. Assuming the grid D.-C. potential to be changed 70 to some other value, as M_{13} , with respect to the neutral, the voltage wave of grid 10 will then be G_{14} . The point of intersection thereof with cathode curve M will be m_2 , at which point the arc will be transferred to anode 4. The time of trans- 75

fer of the arc from anode to anode, and the rectifier D.-C. output voltage varying in accordance therewith, may, therefore, be controlled by varying the D.-C. potential impressed on the grids.

5 Figure 23 shows means for maintaining a constant current in a rectifier load circuit by the regulation of the rectifier D.-C. output voltage through the varying of potentials impressed on the rectifier grids. The neutral point 21 of the 10 windings 19, which impress A.-C. potentials on the rectifier grids, is connected to a rheostat 59 across the rectifier D.-C. output circuit. The rheostat is operated by a motor 60 controlled by a current relay 61. The relay is connected to a 15 shunt 62 in the rectifier D.-C. output circuit. So long as the current in the rectifier D.-C. output circuit remains within predetermined limits, the relay remains in the neutral position. If the current is too low, contact 63 of the relay is closed 20 and the motor is operated to move the rheostat arm in clockwise direction, reducing the D.-C. potential impressed on the grids in series with the A.-C. potential from winding 19, thereby raising the rectifier D.-C. output voltage until the load 25 current is restored to a value within the predetermined limits when contact 63 is again opened. If the load current is too high, contact 64 is closed causing the rheostat arm to move in counterclockwise direction, thereby reducing the rectifier D.-C. voltage until the load current is 30 again restored to a value within the predetermined limits.

Fig. 24 shows means for limiting a rectifier load by the regulation of the rectifier D.-C. output voltage through the varying of potentials impressed on the rectifier grids. In this embodiment, the potentiometer 43 is connected across the rectifier D.-C. output circuit, as in Fig. 7. Two load-limiting steps are shown in Fig. 24, 40 as controlled by current relays 65 and 66 connected to shunt 67 in the rectifier D.-C. output circuit. When the load current exceeds a predetermined value, the relay 65 closes its contact, short-circuiting part of the resistance in potentiometer 43, thereby raising the potential of connection point 23 with respect to the cathode. The transfer of the arc from one anode to another is, therefore, retarded and the rectifier D.-C. output voltage is reduced. If the current rises still higher after relay 65 has operated, relay 55 66 then operates short-circuiting more of the resistance and thereby further reduces the rectifier D.-C. output voltage.

Numerous modifications are possible in the means operating by control of the rectifier D.-C. output voltage for maintaining constant current in the rectifier load circuit, as shown in Fig. 23, and for limiting the rectifier load, as shown in Fig. 24, and any of the means hereinbefore described for rectifier D.-C. output voltage regulation may be employed.

In the hereinbefore described rectifier D.-C. output voltage regulating means, the electric field between cathode and anodes is modified and the regulation thereby obtained by impressing on the rectifier grids potentials of such magnitude and so phased with respect to the anode waves as to prevent transfer of the arc to successive anodes until the intersection point of the anode waves is passed. The electric field between cathode and anodes may, however, be modified and the desired rectifier D.-C. output voltage regulation obtained by impressing on the grids potentials of such magnitude and so phased that the 70 arc is transferred to successive anodes before

the intersection point of the anode waves is reached. The latter method of control will be clear by reference to Figs. 25 and 13 in connection with Fig. 1.

In Fig. 25, E₂ E₃ E₄ . . . represent, respectively, the voltage waves on anodes 2, 3, 4 . . . . Assuming anode 3, corresponding to voltage wave E₃, is in operation, then, if the electric field between the cathode and anode 3 is modified by impressing potentials on the corresponding grid so that the potential between the cathode and said anode is reduced below the potential between the cathode and succeeding anode 4 at a point b, before intersection point X is reached, the arc will be transferred to anode 4 at said point b. The rectifier D.-C. output voltage wave will have the shape shown in the heavy line in Fig. 25 and the rectifier D.-C. output voltage will have the average value of line B. If potentials impressed on grid 9 are varied so that the points at which the arc is transferred to anode 4 are a or c, the rectifier D.-C. output voltage wave will have the values represented by lines A and C, respectively. In Fig. 13 is illustrated one means for effecting the result described in connection with Fig. 25. In this embodiment wave G₁₅ represents the potential of the grid corresponding to the anode whose voltage wave is E₅. Grid voltage wave G₁₅ is shown as leading, for example, by 60 degrees the corresponding anode wave E₅. With different D.-C. potentials B₄ B₅ B₆ impressed on the grid, the zero points of grid potential are a₁₁ b₁₁ c₁₁. Since the grid voltage leads the corresponding anode voltage, the points at which the arc is transferred occur at a₁₂ b₁₂ c₁₂ before the intersection X of E₅, with the succeeding anode voltage wave, is reached. The rectifier D.-C. output voltage is, therefore, regulated by varying the D.-C. potential impressed on the grids. Other control means disclosed herein may be used to effect the rectifier D.-C. output voltage regulation which operates as described in connection with Fig. 25.

Various embodiments of my invention have been described herein for the purpose of illustration. It will be understood, however, that modifications in the structures disclosed may be made within the spirit of the invention, and without departing from the scope thereof as defined in the appended claims.

The invention claimed is:

1. In an electrical system, the combination with an electric current rectifier of the metallic vapor arcing type having an anode, and a control electrode, and means for impressing A.-C. potentials on said anode, of means for impressing on said control electrode voltage waves corresponding in frequency to harmonics of the potentials impressed on said anode, and means for impressing D.-C. potentials on said control electrode.

2. The combination in a rectifier system comprising an electric current rectifier of the metallic vapor arcing type having an anode, and a control electrode, input and output circuits, and means for impressing A.-C. potentials on said anode, of means for impressing on said control electrode voltage waves corresponding to harmonics of the potentials impressed on said anode, means associated with said output circuit for impressing D.-C. potential on said control electrode, and means responsive to changes in an electrical condition in at least one of said circuits for controlling said voltage waves impressed upon said control electrode.

3. The combination in a rectifier system com-

- prising an electric current rectifier of the metallic vapor arcing type having an anode, and a control electrode, and means for impressing A.-C. potentials on said anode, of means for impressing D.-C. potential on said control electrode, means for impressing on said control electrode voltage waves corresponding in frequency to harmonics of the potentials impressed on said anode, and means in operative relation with the means for impressing the voltage waves on said control electrode for controlling said voltage waves.
4. In combination with a rectifier system comprising an electric current rectifier of the metallic vapor arcing type having an anode, and a control electrode, an output circuit, and means for impressing A.-C. potentials on said anode, of means for impressing D.-C. potential on said control electrode, means for impressing on said control electrode voltage waves corresponding in frequency to harmonics of the potentials impressed on said anode and means responsive to an electrical condition in said output circuit and in operative relation with the means for impressing the voltage waves on said control electrode for controlling said voltage waves.
5. In a current rectifying system comprising an electric current rectifier of the metallic vapor arcing type having a casing, an anode, a cathode, and a control electrode, a source of A.-C. connected with and supplying said anode, a circuit connected with and receiving D.-C. from said cathode, means for controlling the voltage in said D.-C. circuit comprising means connected with said source of A.-C. for impressing a voltage on said control electrode, a resistance connecting said control electrode with said D.-C. circuit to impress a direct current voltage on said electrode, an oscillating contact for gradually varying the voltage impressed on said control electrode, and a coil moving said contact in response to variations of voltage in said D.-C. circuit.
6. In a current rectifying system comprising an electric current rectifier of the metallic vapor arcing type having a casing, an anode, a cathode, and a control electrode, a source of A.-C. connected with and supplying said anode, a circuit connected with and receiving D.-C. from said cathode, means for controlling the voltage in said D.-C. circuit comprising means connected with said source of A.-C. for impressing voltage waves on said control electrode, a resistance connecting said control electrode with said D.-C. circuit to impress a direct current voltage on said electrode, an oscillating contact for gradually varying the voltage impressed on said control electrode, and a plurality of cooperating coils energized from said D.-C. circuit for operating said contact, one of said coils being responsive to current and the other of said coils being responsive to voltage.
7. In a current rectifying system comprising an electric current rectifier of the metallic vapor arcing type having a casing, an anode, a cathode, and a control electrode, a source of A.-C. connected with and supplying said anode, a circuit connected with and receiving D.-C. from said cathode, means for controlling the voltage in said D.-C. circuit comprising means connected with said source of A.-C. for impressing voltage waves on said control electrode, a resistance connecting said control electrode with said D.-C. circuit to impress a direct current voltage on said electrode, an oscillating contact for gradually varying the voltage impressed on said control electrode, and a coil connected with said A.-C.
- source and responsive to the current therein for operating said contact.
8. In a current rectifying system comprising an electric current rectifier of the metallic vapor arcing type having a casing, an anode, a cathode, and a control electrode, a source of A.-C. connected with and supplying said anode, a circuit connected with and receiving D.-C. from said cathode, means for controlling the voltage in said D.-C. circuit comprising means connected with said source of A.-C. for impressing voltage waves on said control electrode, a resistance connecting said control electrode with said D.-C. circuit to impress a direct current voltage on said electrode, an oscillating contact for gradually varying the voltage impressed on said control electrode, a motor for operating said contact, and a current relay connected into said D.-C. circuit and controlling said motor in response to the load thereon.
9. In a rectifier system comprising an electric current rectifier of the metallic vapor type having an anode and a control electrode, a circuit for impressing alternating current on said anode, a direct current output circuit, means for controlling the voltage of said output circuit by varying the shape of the wave thereof comprising means in operative relation with said alternating current circuit for impressing voltage waves on said control electrode and for changing the phase thereof with respect to the phase of the potentials impressed on said anode, and means having connections for impressing direct current voltage on said electrode from the said output circuit, the said connections including a reactance coil included therein for reducing in said connections ripple currents received therein from said output circuit.
10. In a rectifying system comprising an electric current rectifier of the metallic vapor arcing type having an anode, a cathode, and a control electrode, a source of alternating current connected with and supplying said anode, an output circuit connected with and receiving direct current from said cathode, means for controlling the voltage of the said output circuit comprising means connected with said source of alternating current for impressing a voltage on said control electrode, a resistance divided into sections connecting said control electrode with said output circuit for impressing direct current voltage from said output circuit on said control electrode, and means for varying said resistance by rendering ineffective sections thereof to thereby vary the magnitude of the said direct current voltage impressed on said control electrode, the last said means comprising a plurality of relays selectively actuated in dependence upon the magnitude of the current flowing in said output circuit.
11. In combination with a rectifier system comprising an electric current rectifier of the metallic vapor arcing type having an anode, a cathode, and a control electrode, a source of alternating current connected with said anode for impressing alternating current potentials thereon, a direct current output circuit connected with said cathode to be supplied with direct current from said rectifier, of means comprising a transformer having a primary winding connected with said source of alternating current and an open delta connected secondary winding connected with and operative to impress voltage waves upon said control electrode corresponding in frequency to harmonics of the potentials impressed on said anode, and means responsive to current flow in said out-

- put circuit and in operative relation with said means for impressing voltage waves on the said control electrode for controlling said voltage waves.
- 5 12. In combination with a rectifier system comprising an electric current rectifier of the metallic vapor arcing type having an anode, a cathode, and a control electrode, a source of alternating current connected with said anode to supply alternating current to said rectifier to be converted into direct current, and an output circuit connected with said rectifier to be supplied with direct current therefrom, of means comprising a transformer having a primary winding connected 10 with said source of alternating current and an open delta connected secondary winding connected with said control electrode to impress thereon voltage waves corresponding in frequency to harmonics of the voltages of the said source 15 of current connected with said anode, means responsive to flow of current in the said output circuit and in operative relation with said transformer for controlling said voltage waves on said control electrode, and a source of direct current connected with said output circuit and said delta connected winding for impressing direct current voltage on said control electrode.
- 20 13. In combination with an electric current rectifier of the vapor arcing type having an anode and a control electrode, a source of A.-C. connected with and supplying said anode, and a circuit connected with and receiving D.-C. from said rectifier, of means for controlling the voltage of said circuit comprising means connected 25 with said source of A.-C. for impressing voltage waves on said control electrode, a voltage divider connected across said circuit, and means connecting said voltage divider with said electrode whereby D.-C. voltage is impressed on said electrode from said circuit.
- 30 14. In combination with an electric current rectifier of the vapor arcing type having an anode, and a control electrode, a source of A.-C. connected with and supplying said anode, and a circuit connected with and receiving D.-C. from said rectifier, of means for controlling the voltage of said circuit comprising means connected 35 with said source of A.-C. for impressing voltage waves on said control electrode, a voltage divider connected across said circuit, and means connecting said voltage divider with said electrode whereby D.-C. voltage is impressed on said electrode from said circuit.
- 40 15. In combination with an electric current rectifier of the vapor arcing type having an anode, and a control electrode, a source of A.-C. connected with and supplying said anode, and a circuit connected with and receiving D.-C. from said rectifier, of means for controlling the voltage of said circuit comprising means connected 45 with said source of A.-C. for impressing voltage waves on said control electrode, a voltage divider including a reactance connected across said circuit, and means connecting said voltage divider with said electrode whereby D.-C. voltage is impressed on said electrode from said circuit and ripple current received therefrom is suppressed.
- 50 16. In combination with an electric current rectifier of the vapor arcing type having an anode, and a control electrode, a source of A.-C. connected with and supplying said anode, and a circuit connected with and receiving D.-C. from said rectifier, of means for controlling the voltage of said circuit comprising means connected 55 with said source of A.-C. for impressing voltage waves on said control electrode, a voltage divider including an inductance connected across said circuit, and means connecting said voltage divider with said electrode whereby D.-C. voltage is impressed on said electrode from said circuit and voltage ripples of said voltage is suppressed.
- 70 17. In combination with an electric current rectifier of the vapor arcing type having an anode, and a control electrode, a source of A.-C. connected with and supplying said anode, and a circuit connected with and receiving D.-C. from said rectifier, of means for controlling the voltage of said circuit comprising means connected 75 with said source of A.-C. for impressing voltage waves on said control electrode, a voltage divider connected across said circuit, means connecting said voltage divider with said electrode whereby D.-C. voltage is impressed on said electrode from said circuit, and means for varying the connection of the last said means with said voltage divider to thereby gradually vary the magnitude of said D.-C. voltage impressed on said electrode.
- 80 18. In combination with an electric current rectifier of the vapor arcing type having an anode, and a control electrode, a source of A.-C. connected with said anode and supplying said rectifier, and a circuit connected with and receiving D.-C. from said rectifier, of means for controlling the voltage of said circuit comprising means connected 85 with said source of A.-C. for impressing voltage waves on said control electrode, a voltage divider connected across said circuit, means connecting said voltage divider with said electrode whereby D.-C. voltage is impressed on said electrode from said circuit, means for varying the connection of the last said means with said voltage divider to thereby gradually vary the magnitude of said D.-C. voltage impressed on said electrode, and means operable responsive to and in dependence upon changes in conditions of said circuit for actuating the said means for varying the said connection of the said voltage divider with the said electrode.
- 90 19. In an electric translating circuit, a source of alternating potential, an electric valve provided with an anode, a cathode, and a control grid, a saturable transformer for energizing said grid from said source, and means for controlling the saturation of said transformer for controlling the conductivity of said valve.
- 95 20. The method of controlling the conductivity of a grid controlled electric valve excited from a saturable transformer connected to a source of alternating potential which comprises varying the saturation of said transformer to vary the point in the cycle of alternating potential at which said valve is rendered conductive.
- 100 21. In a regulating system, an electric circuit, an electric valve provided with an anode, a cathode and a control electrode for controlling an electrical condition of said circuit, a source of alternating potential connected to energize the anode of said valve, means for impressing on said control electrode an alternating potential of substantially constant value and fixed phase relation 105 with respect to said anode potential, and means for superimposing a unidirectional potential varying in accordance with the electrical condition to be regulated on the alternating potential of said control electrode in a manner to vary the conductivity of said valve in proportion to the deviation from a predetermined value of the electrical condition to be regulated.
- 110 22. In an electric current converting system, the combination with an alternating current cir- 115

- cuit, a direct current circuit, and means comprising an electric valve having an anode and a cathode constituting spaced electrodes for the flow of current therebetween, of means for controlling said flow of current comprising an element of said valve other than said electrodes, means for impressing on said element a voltage comprising an alternating component corresponding in frequency to a harmonic of the voltage frequency of said alternating current circuit and a unidirectional component, and means for varying the magnitude of said unidirectional component.
23. In an electric current converting system, the combination with an electric current supply circuit, an electric current work circuit, and means comprising an electric valve having an anode and a cathode interconnecting said circuits and constituting spaced electrodes for the flow of current therebetween, of means for controlling said flow of current comprising an element of said valve other than said electrodes, means for impressing a unidirectional voltage component on said element, means comprising a saturable transformer for impressing an alternating voltage component on said element, and means for varying the said alternating voltage component comprising means for varying the saturation of said transformer.
24. In an electric current converting system, the combination with an alternating current circuit, a direct current circuit, and means comprising an electric valve having an anode and a cathode interconnecting said circuits and constituting spaced electrodes for the flow of current therebetween, of means for controlling said flow of current comprising an element of said valve other than said electrodes, means for impressing on said element alternating voltage components having wave fronts steeper than the corresponding portions of sinusoidal waves of the same amplitude as said voltage waves and of the same frequency as the voltage waves of said alternating current circuit, means for impressing a unidirectional voltage component on said element, and means for varying the said alternating voltage component.
25. In an electric current converting system, the combination with an alternating current circuit, a direct current circuit, and means comprising an electric valve having an anode and a cathode interconnecting said circuits and constituting spaced electrodes for the flow of current therebetween, of means for controlling said flow of current comprising an element of said valve other than said electrodes, means for impressing on said element a voltage comprising an alternating component corresponding in frequency to a harmonic of the voltage frequency of said alternating current circuit and a unidirectional component, and means for varying the magnitude of said unidirectional component.
26. In an electric current converting system, the combination with an electric current supply circuit, an electric current work circuit, and means comprising an electric valve having an anode and a cathode interconnecting said circuits and constituting spaced electrodes for the flow of current therebetween, of means for controlling said flow of current comprising an element of said valve other than said electrodes, a control circuit for said element comprising a source of negative bias potential and a saturable transformer, a source of control potential for energizing said transformer, and means comprising an element of said transformer operable in dependence upon variations in said flow of current through said valve to control the saturation of said transformer, to thereby modify the effect of said control circuit.
27. In an electric current converting system, the combination with an alternating current circuit, a direct current circuit, and means comprising an electric valve of the vapor arcing type having an anode and a cathode interconnecting said circuits and constituting spaced electrodes for the flow of current therebetween, of means for controlling said flow of current comprising an element of said device other than said electrodes, and means for impressing on said element voltage waves corresponding in frequency to harmonics of the voltage of said alternating current circuit for determining the moments of initiation of the periods of said flow of current between said anode and cathode.
